(57) **CLAIM**

The ornamental design for an umbrella with hook and loop fastener edges design, as shown and described.

DESCRIPTION

FIG. 1 is a perspective view of the umbrella with hook and loop fastener edges design of the present invention;

FIG. 2 is a front view of the umbrella with hook and loop fastener edges design of FIG. 1;

FIG. 3 is a top view of the umbrella with hook and loop fastener edges design of FIG. 1; and,

FIG. 4 is a bottom view of the umbrella with hook and loop fastener edges design of FIG. 1.

The broken line shown on the outer surface of the umbrella represents stitching and forms part of the claimed design. All other broken lines are included for the purpose of illustrating portions of the article and forms no part of the claimed design.

1 Claim, 4 Drawing Sheets
